CLAIM

The ornamental design for an interface device, as shown and described.

DESCRIPTION

FIG. 1 is a top front left side perspective view of an interface device showing our new design;

FIG. 2 is a top view of the interface device shown in FIG. 1;

FIG. 3 is a bottom view of the interface device shown in FIG. 1;

FIG. 4 is a front view of the interface device shown in FIG. 1;

FIG. 5 is a rear view of the interface device shown in FIG. 1;

FIG. 6 is a left side view of the interface device shown in FIG. 1;

FIG. 7 is a right side view of the interface device shown in FIG. 1;

FIG. 8 is a bottom front left side perspective view of the interface device shown in FIG. 1;

FIG. 9 is a bottom front right side perspective view of the interface device shown in FIG. 1;

FIG. 10 is a bottom rear left side perspective view of the interface device shown in FIG. 1;

FIG. 11 is a bottom rear right side perspective view of the interface device shown in FIG. 1;

FIG. 12 is a top front right side perspective view of the interface device shown in FIG. 1;

FIG. 13 is a top rear left side perspective view of the interface device shown in FIG. 1; and,

FIG. 14 is a top rear right side perspective view of the interface device shown in FIG. 1.
